UNITED STATES PATENT OFFICE.

ARTEMUS WELSH AND ELMER WELSH, OF SCOTTDALE, PENNSYLVANIA.

OLIVER.

SPECIFICATION forming part of Letters Patent No. 357,255, dated February 8, 1887.

Application filed October 26, 1886. Serial No. 217,277. (No model.)

To all whom it may concern:

Be it known that we, ARTEMUS WELSH and ELMER WELSH, citizens of the United States, residing at Scottdale, in the county of Westmoreland and State of Pennsylvania, have invented a new and useful Improvement in Oliver's, of which the following is a specification.

Our invention relates to an improvement in olivers; and it consists in the peculiar construction and combination of devices, that will be more fully set forth hereinafter, and particularly pointed out in the claims.

In the drawings, Figure 1 is a perspective view of an oliver embodying our improvements. Fig. 2 is a detailed sectional view of the same taken on the line $x-x$ of Fig. 1. Fig. 3 is a similar view taken on the line $y-y$ of Fig. 1. Fig. 4 is a detailed perspective view of the bottom and upper dies used for shearing.

A represents an anvil, which is provided on its upper side with a horizontal transverse dovetailed groove, B.

C represents a die which is placed on the upper side of the anvil, and is provided on its under side with a dovetailed tongue, D, that fits in the groove B. This enables the die to be very readily removed from the anvil when desired.

At a suitable distance from the anvil is secured the frame E of the oliver, comprising the vertical sides or standards F, the rearwardly and upwardly inclined arms G, projecting from the said sides or standards, and the cross-bar H, connecting the outer ends of the said arms. In the upper ends of the sides or standards are bearing-boxes I, in which is journaled a rock-shaft, K.

L represents a rocking arm, which projects from the front side of the rock-shaft. A spring, M, connects the cross-bar H with the rocking arm, and serves to balance the latter and to normally raise it to an elevated position, as shown in solid lines in Fig. 1. The outer end of the rocking arm is provided on one side with a depending web or plate, N, having a curved slot, O.

P represents the hammer, which is provided on its upper side with a vertical transverse groove, R, to receive the outer end of the rocking arm. A pivotal bolt, S, passes through

transverse openings which are made in the upper side of the hammer and in the outer end of the rocking arm, so as to pivot the hammer to the outer end of the rocking arm and adapt it to turn or incline longitudinally thereon.

T represents a bolt, which extends through the slot O and through a transverse opening made in the hammer, and on the inner threaded end of the said bolt is screwed a clamping-nut, U, the function of which is to tighten the bolt so as to clamp the hammer to the web or plate N at any desired longitudinal inclination. In the under side of the hammer is a transverse dovetailed groove, V. A die, W, has on its upper side a dovetailed tongue, X, to enter the groove V, and thus secure the die to the under side of the hammer. A treadle, Y, is connected to the rock-shaft; or it may be connected to the rocking arm in any suitable manner, so that when the operator places his foot upon the treadle the rocking arm will be lowered and cause the hammer to strike on the face of the anvil.

By pivoting the hammer to the outer end of the rocking arm, so that it may turn longitudinally thereon, and providing the clamping-bolt to secure the hammer at any desired longitudinal inclination, the hammer will be caused to strike upon the anvil at any desired angle, according to the various requirements of the articles that are being forged.

In order to adapt the oliver for use in shearing or cutting metallic plates or bars, we provide the dies which are illustrated in Fig. 4, and are adapted to be secured to the anvil and the hammer in lieu of the dies C and W.

The spring M has one or more coils or convolutions between the point of attachment to the cross-bar H and the rock-shaft K, so that as the hammer is operated said coils will be wound up by the downward movement of the hammer, imparted through the treadle, and automatically unwound to raise the hammer and treadle. The cross-bar H is raised or elevated some distance above the rock-shaft K and the hammer, so that the action of the spring M serves to suspend, balance, or poise the hammer for the downward stroke.

Having thus described our invention, we claim—

1. In an oliver, the rock-arm L, combined

with the hammer adjustable on the arm in an arc of a circle, for the purpose set forth.

2. In an oliver, the combination of the rocking arm L and the hammer pivoted to the said arm, and means for clamping the hammer rigidly to the arm, for the purpose set forth, substantially as described.

3. The combination, in an oliver, of the rocking arm L, having the plate or web N, provided with the curved slot O, the hammer pivoted to the rocking arm, and the clamping-

bolt extending through the curved slot and secured to the hammer, for the purpose set forth, substantially as described.

In testimony that we claim the foregoing as our own we have hereto affixed our signatures in presence of two witnesses.

ARTEMUS WELSH.

ELMER WELSH.
